UNITED STATES PATENT OFFICE.

JOHN S. BRENNAN, OF MILWAUKEE, WISCONSIN.

WATER HEATER.

Application filed August 28, 1922. Serial No. 584,689.

To all whom it may concern:

Be it known that I, JOHN S. BRENNAN, a citizen of the United States, and resident of Milwaukee, in the county of Milwaukee and State of Wisconsin, have invented certain new and useful Improvements in Water Heaters; and I do hereby declare that the following is a full, clear, and exact description thereof.

10 This invention relates to hot water heaters of the type in which a burner is located adjacent the lower portion of a casing and a water coil or pipe is located above the burner and within the casing.

15 In hot water heaters as heretofore constructed, difficulty has been experienced due to condensation of moisture upon the outer surface of the coils or pipes. These heaters are usually connected with a hot water tank 20 in which the heated water is stored. When, however, water is drawn from the tank, it frequently happens that all of the hot water is withdrawn and cold water is then drawn from the tank. When this occurs, cold water 25 circulates through the heating coils thereby chilling them and causing moisture in the products of combustion to condense upon the outer surface of the coils. This water drips or runs down the coils and falls upon the 30 burners, thereby markedly interfering with their operation and frequently completely extinguishing the fire. Other cause, such as defective relative arrangement of pipe connection with the tank may cause this undesirable circulation of cold water through the 35 heating coils, with the consequent detrimental results.

It is to overcome these defects that the present invention is designed, and it is therefore a primary object of this invention to provide a heater in which condensation will not interfere with the burner or flame or with the efficient operation of the heater.

Further objects are to provide a hot water 45 heater in which the lower header performs the dual function of a distributor of the incoming water to the coils, and of means for taking care of the drip or condensation; to provide a hot water heater in which the coils 50 substantially fill the casing thereby retarding the flow of products of combustion sufficiently to allow the maximum amount of heat to be extracted therefrom; and to provide a heater in which the support or base 55 further cooperates with the heater to catch

any excessive drip and allow it to subsequently evaporate.

This invention is applicable to any type of hot water heater, whether it employs gas, oil, alcohol, or other fuel. However, the embodiment of the inventor chosen for illustration, is an oil burning heater; but it is to be taken as illustrative rather than limiting, as the invention is to be limited only as set forth in the appended claim.

Referring to the drawings,

Figure 1 is a front elevation of a heater with parts broken away to show the interior construction.

Figure 2 is a vertical sectional view on the 70 line 2—2 of Figure 1.

Figure 3 is a vertical sectional view of the lower header, such section being taken on the line 3—3 of Figure 4.

Figure 4 is a plan view of the lower 75 header.

Figure 5 is a horizontal sectional view through the casing and heating coils.

Figure 6 is a horizontal sectional view 80 of the upper header.

The device comprises a casing which may be formed of two substantially similar half sections, and comprises an enlarged oval shaped bottom portion 1 and cylindrical portion 2 extending upwardly therefrom and terminating in the cap 3 provided with a flue receiving aperture 4.

These half sections may be joined at several points by means of the bolts 5 passing through the apertured ears formed integrally with the half sections. The rear half section is provided with a downwardly extending lug 6 to which is riveted the upper end of a standard 7 and the lower end of said standard being secured to an upward projecting portion 8 of a base 9.

This base or support is provided with the recessed portion 10 on its upper side for a purpose hereinafter described. The front half section is cut out adjacent its lower edge and is provided with a pivotally mounted door 11 which in Figure 1 is shown in its upwardly extending position and Figure 2 in its closed position.

This door is adapted to be received in catch 12 when it is closed or in its lowermost 105 position.

The pair of burners indicated generally at 13 and 14 are mounted within the lower portion of the enlarged oval shaped portion 1 of the casing. They are fed from a tank 110

or container 15 by means of a main supply pipe 16 and branch pipes 17, such branch pipes being independently controlled by means of the manually adjustable valves 18.

5 The burner and supply tank structure may be supported by means of a bracket 19 and secured to the standard 7 by clips 20 clamped around the pipe 16.

As may be seen from Figure 5 a plurality 10 of heating elements in the form of helical coils of pipe 22 substantially fill the interior portion of the cylindrical part 2 of the casing. These coils are mounted between, communicate with, and are supported by upper 15 and lower headers 23 and 24, respectively. These headers are each provided with an enlarged or flanged portion 25 received in a suitable aperture in the rear half section of the casing, and have projecting therefrom, a 20 threaded extension 26. The cold water supply pipe 27 and the hot water supply pipe 28 may be attached to the extension 26 by means of an internally threaded sleeve or union 29, such sleeves also serving to clamp 25 the headers in position. The ends of the coils of pipes 22 may be brazed or welded within apertured bosses 30, formed upon the sides of the upper header and within apertured bosses 31 extending upwardly from 30 lower header as may be seen from Figures 4 and 6.

The lower header 24 is of oval shape and is provided with a depressed or hollow upper portion which may be formed by the 35 wall 32 and the marginal flange 33. The marginal flange may be provided with one or more notches 34 as may be seen from Figures 1 and 4. The lower portion or bottom wall of this header merges into a downwardly extending point or apex 35. This 40 apex or downwardly extending projecting portion 35 is located between the burners 13 and 14.

This hot water heater is protected against 45 harmful effects from condensed moisture upon the outer surface of the coils 22, which condensation may be caused by inadvertent circulation of cold water through the coils while the heater is in operation. Any condensation which is formed will be caught 50 by the depressed upper portion of the lower header. When sufficient liquid has been caught by the header it will flow through the notched portion and will be guided 55 downwardly to the lowest portion thereof, i. e. to the projecting portion 35. It is to be noted that this portion 35 is located between the burners and directly above the

hollow portion 10 of the base or support 9. Any water, therefore, that drips from this 60 downwardly projecting portion will be caught in the hollow base and can subsequently evaporate.

It will be seen, therefore, that a hot water heater has been provided, in which condensation upon the outer surface of the coils is 65 prevented from interfering with the efficient operation of the burners.

It will further be seen due to the close positioning of the coils 22 which substantially 70 fill the cylindrical portion 2 of the casing, that the maximum of heat is extracted from the products of combustion.

It will further be seen that the lower header serves the dual purpose of a header 75 and of means for catching any moisture that may drip from the coils.

It will further be seen that even the prolonged circulation of cold water through the heating coils, from any cause whatsoever, 80 will not at any time interfere with the normal operation of the burners as provision has been made for taking care of any water which may flow from the header without allowing such water to contact with the 85 burners.

What is claimed is:

A water heater comprising a pair of spaced burners, a casing mounted above said burners and having a hood enclosing the upper portion of said burners and contracting to a cylindrical upper portion extending vertically upwardly from said hood, a heating coil located within the cylindrical portion of said casing, a lower header located 95 within said hood and conforming roughly to the outline of said hood and spaced therefrom and located above said burners and communicating with the lower end of said heating coil, said lower header having an upturned marginal flange provided with a notch and having a downwardly tapered lower portion terminating in a point, said point forming the lowermost portion of said header and being located between said 105 burners, whereby condensation caught by said header will flow through said notch and downwardly along the tapered lower surface of said header and will fall between the burners from the pointed lower end of 110 said header.

In testimony that I claim the foregoing I have hereunto set my hand at Milwaukee, in the county of Milwaukee and State of Wisconsin.

JOHN S. BRENNAN.
